UNITED STATES PATENT OFFICE.

COLOMAN ROZÁR, OF NUREMBERG, GERMANY.

DEVICE FOR CASTING JUSTIFYING-SPACES IN COMBINED TYPE CASTING AND SETTING MACHINES.

SPECIFICATION forming part of Letters Patent No. 717,763, dated January 6, 1903.

Application filed November 20, 1900. Serial No. 37,133. (No model.)

To all whom it may concern:

Be it known that I, COLOMAN ROZÁR, a subject of the Emperor of Austria-Hungary, residing at 34 Maagfeldstrasse, Nuremberg, Germany, have invented certain new and useful Improvements in Means for Casting Justifying-Spaces in Combined Type Casting and Setting Machines, of which the following is a specification.

10 The present invention relates to type-setting machines in which the type are cast in a given order and at the same time composed into lines by aid of a perforated strip or so-called "perforated register." This register represents the different characters and the spaces requisite for each line in the form of consecutive transverse rows of holes, the various combinations of perforations enabling the various characters, as well as spaces of 15 different thickness, to be cast. In constructing the perforated strip the hole combinations representing the spaces are selected and so arranged that the spaces cast in accordance therewith when inserted in the line bring it 20 to the requisite uniform length—that is to say, justify the line.

To provide means for casting in a type casting and setting machine spaces according to a perforated strip of this kind is the object 25 of the present invention.

In the accompanying drawings, Figure 1 is a plan view of a section of such a register-strip as is employed in carrying out my invention. Fig. 2 is a diagrammatic view illustrating the various electrical circuits. Figs. 3 to 6 are details of part of the electrical devices employed in carrying out my invention, Fig. 4 being a sectional view on the line B-B of Fig. 3 and Fig. 6 being a side elevation of 30 the part shown in Fig. 5. Fig. 7 is an end elevation of the mechanical parts of my improved justifying mechanism. Fig. 8 is a view taken on the line A-A of Fig. 7. Fig. 9 is an elevation illustrating part of the device 35 shown in Fig. 8. Fig. 10 is a plan view illustrating features shown in Fig. 8, partly broken away. Figs. 11 to 20 are detail views.

The perforated register for actuating the mechanism and which strip is illustrated in 40 Fig. 1 consists of an endless band of paper having a series of perforations, the rows of perforations representing the type characters

being indicated by the letters inscribed beside them. The perforation or hole IV determines the end of a line, those in the row III 45 determine the position of the spaces in a line, and those in the rows I and II the thickness of the spaces for the line represented by the various transverse rows of holes between the hole IV shown and the next similar succeeding perforation in the strip. While the register is being prepared the strip moves from right to left, so that perforations corresponding to those marked II III IV are formed at the end of the series of perforations representing each line of matter. When the types and spaces are being cast, the perforated strip or register moves from left to right, as indicated by the arrow, so that at the beginning of each new line the hole IV is the first 50 to come into operation in order to push to one side the line just composed and make room for the next line to be composed. After this the rows of holes I II properly adjust a stop for the core of the mold, so that the spaces 55 which are cast when the holes III representing spaces come into operative position bring the lines to the prescribed length. By reference to Fig. 1 it will be seen that the perforations or holes in the strip are arranged in 50 seven longitudinally-extending rows or zones, numbered, respectively, 1 2 3 4 5 6 7. In operation the register-strip passes between plate 8, Fig. 2, and seven contact-springs 1' 2' 3' 4' 5' 6' 7', corresponding to the aforesaid zones 65 of the strip, being advanced by suitable mechanism step by step, each interval being the same as the distance between the transverse rows of holes. At each adjustment of the register those contact-springs whose ends 70 above the plate 8 are over perforations in the strip are brought into electrical connection with the plate 8 and close corresponding electrical circuits. By such circuits suitable mechanical means are caused to act in such a 75 way that a matrix for producing a character represented by the combination of perforations then in operative position comes in front of the mold and causes the proper type 80 to be cast. This operation as regards the 85 casting of type has been fully set forth in the specification of United States Letters Patent No. 628,631 and forms no part of the present invention, which relates only to means for 90 95 100

casting justifying-spaces which are represented on the register-strip by the transverse rows of perforations designated I II III IV.

My invention is particularly designed for use in connection with the type-casting machine described and illustrated in the aforesaid Patent No. 628,631.

For the purpose of assisting in an understanding of my invention Figs. 1 and 2 herein illustrate a register-strip and an arrangement of electric circuits similar to those shown in said patent supplemented by the present invention. The latter only, however, is illustrated in the other views.

Referring now to Fig. 2, it will be seen that the contact-springs 1' to 7' are electrically connected by wires 9 with contact-plates 1^x 2^x 3^x 4^x 5^x 6^x 7^x, mounted on a plate 10 of insulating material. On said plate 10, are also arranged a series of contact-plates 1^{xx} 2^{xx} 3^{xx} 4^{xx} 5^{xx} 6^{xx} 7^{xx}, these latter being arranged in the same radial lines as contacts 1^x to 7^x and electrically connected by wires 11 with seven insulated contacts 1" 2" 3" 4" 5" 6" 7" on a switch-lever 12. A rotary shaft 13, passing through the center of the plate 10, has an insulated arm 14, on which are carried contacts 16 17, that are electrically connected by means of a metal strip 15. As the shaft 13 rotates in the direction of the arrow the contacts 16 17 slide over the contact-plates 7^x 7^{xx} 6^x 6^{xx} 1^x 1^{xx} to 5^x 5^{xx}, and thus successively close the several circuits, each including the two contacts that are in the same radial line. On the plate 10 in the paths of the rotatable contacts 16 17 and between the contacts 7^x 7^{xx} and 5^x 5^{xx} are arranged two metal plates, which, however, are not included in any electrical circuit, being merely for the purpose of preventing wearing away of the plate 10. A battery 20 forms the source of current for the several circuits hereinbefore referred to, the positive pole of said battery being connected with the plate 8 by a wire 21 and the negative pole connected with the contacts 1" to 7" of the switch-lever 12, as required, in a manner to be more particularly explained hereinafter. The shaft 13 is connected with the mechanism employed for advancing the perforated strip in such a manner that once during each revolution of the contacts 16 17 and during the time they are passing over the strips 18 19 said register or perforated strip is advanced a distance equal to that separating the transverse rows of holes, and the said register-strip then rests or remains stationary with one row of holes under the free ends of the contact-springs 1' to 7', while the contacts 16 17 pass over the plates 7^x 7^{xx} to 5^x 5^{xx}. For instance, when the row containing the combination of holes representing the letter "M" on the register-strip, (illustrated in Fig. 1,) which consists of four holes in the zones 7 1 2 4, is under the contact-springs four circuits are successively closed during one revolution of the shaft 13 as the sliding contacts 16 17 pass over the plates 7^x 7^{xx}, 1^x 1^{xx},

2^x 2^{xx}, 4^x 4^{xx}, and these four circuits actuate suitable devices like those and in the manner described in the aforesaid United States Letters Patent No. 628,631, (for example) by which during the remainder of the revolution of the shaft 13 the matrix for the letter "M" comes in front of the mold and the type "M" is cast. During the casting of type the lever 12 occupies the position illustrated in Fig. 2. When the perforated register is again moved on and the hole IV, which is in the longitudinal row or zone 5 thereon, comes under the end of the alined contact-spring 5', the circuit through the plates 5^x 5^{xx} is closed as the sliding contacts 16 17 pass over these plates. By suitable means controlled by the closing of said circuit and not forming part of the present invention the completed line of type is moved aside in order to make room for the next. At the same time a suitable mechanism is connected with the shaft 13 during three succeeding revolutions thereof, which by three distinct movements adjusts the lever 12 from the position illustrated, first, over the tripartite contact 23; secondly, over the tripartite contact 24, and, thirdly, back again into its original position. As the perforated strip is advanced three steps during these three revolutions of the shaft 13—that is, simultaneously with the three adjustments of lever 12—the position of the lever 12 over the contacts 23 or 24 will coincide, respectively, with the positioning of the transverse rows of holes I and II under the contact-springs 1' to 7', and when the row of holes in the register next following that one marked II (which row represents a letter) comes into operation lever 12 again assumes its normal position (shown in the drawings) and enables the first letter of the new line to be cast.

In the preceding paragraphs I have outlined briefly the method of operation of such a machine as is illustrated and described in the United States Letters Patent No. 628,631 with my invention applied thereto. As the casting of type, however, forms no part of my present invention, I will only describe in detail the method of and mechanism for casting justifying-spaces, which mechanism is controlled by the rows of holes in the register-strip marked I and II and by the movements of the switch-lever 12 over the contacts 23 24.

The principle of justifying followed in carrying out the present invention consists in providing types and spaces which are graduated in thickness and vary from each other by relatively small units and in assuming that the words in a line are separated by spaces of medium thickness, the remainder or excess space then being distributed uniformly as far as possible among all the spaces and the undistributed remainder, if any, (which must necessarily contain a less number of units than there are spaces,) allotted by single units to as many of the

spaces as is necessary. For example, I will assume that each of the ordinary or medium spaces has a thickness of ten units and that a line containing eight of such spaces is found to be forty-three units too short. To justify such a line by following the principle above stated, it is necessary to either increase the thickness of each of the spaces in the line by five units and to further increase three of the spaces to the amount of one unit—that is, three of the spaces must be made of the thickness of sixteen units each and five of the spaces given a thickness of fifteen units each—or each of the eight spaces must be increased in thickness by six units and to equalize this five of the spaces reduced in thickness by one unit each, (thus providing three spaces of sixteen units each and five spaces of fifteen units each.) If under the conditions assumed the provisional line is too long by forty-three units, then it is necessary to either reduce the thickness of each of the eight provisional spaces by five units and to further reduce three of such spaces by one unit each or to reduce each of the eight temporary spaces an amount equal to six units and to equalize this afterward increase the thickness of five spaces by one unit each. By either method five spaces having a thickness of five units each and three spaces having a thickness of four units each are provided. The perforations in the rows I II of the register are arranged in such manner as to carry out the principle of justifying above referred to. The perforations or holes in row II indicate the number of units by which each of the spaces in the line represented by the rows of perforations between said row II and the next corresponding row of the register must vary in thickness from the normal or medium spaces—that is, a hole in zone 1 2 3 4 5 of row II indicates a variation in thickness from the normal space of one, two, three, four, or five units, respectively. As usual, the variation required is greater than five units. Said row II generally contains a series of perforations, the required variation being equal to the sum of the numerals designating the zones in which the holes are situated. In Fig. 1, for instance, there are three holes in row II—one each in the zones 2, 3, and 4. This combination of holes consequently represents a variation from the normal equal to the sum of said zone-numerals 2, 3, 4, or nine units, and indicates that each spacing-piece of the succeeding line must vary to the extent of nine units from a normal space. The row of holes marked I never contains but one hole on any of the zone-lines 1 to 5, and this hole indicates, according as it is situated in the zones 1, 2, 3, 4, or 5, the number of spaces among which the remainder or excess of variation required to justify a line must be distributed by single units after the equal distribution of variation to all of the spaces as represented in row II. This

remainder can never amount to more than five units, because in perforating the register-strip the remainder or excess, even in lines of more than ten space-places, is still only divided into ten spaces, the other space-places being filled by spaces of normal thickness. The distribution of spaces according to the principle set forth above permits of having a remainder the total number of units in which is less than half the number of spaces. Whether the variations indicated by the rows I II are to be added to or subtracted from the normal space is indicated by holes in the zones 6 7, a hole in one of said zones always appearing in each of said rows—that is, a hole in zone 7 indicates addition, while a hole in zone 6 indicates subtraction. This is clearly shown in Fig. 1, where the sign of addition is placed above row II and the sign of subtraction above row I. Therefore according to the example illustrated in Fig. 1 the two rows of holes II and I indicate that each of the spaces in the line represented by the rows of perforations between said rows I II and the next succeeding similar rows on the register must be nine units thicker than the normal space, and three of such spaces must then be reduced by one unit each—that is, of the spaces necessary for justifying this line three are to be made eight units thicker and the others nine units thicker than the normal space. The essential problem of the invention is therefore to regulate the core of the mold which becomes operative when the spaces are being cast, so that the spaces prescribed by the rows of holes I II are correctly formed. This is effected by adjusting the core as required by the means controlled by the rows I and II, so that the spaces which vary from the normal space by one unit each will be cast as the rows III successively come into operative position until the requisite number of such spaces is cast, and then the core is automatically adjusted into another position, so that for the rest of the line only spaces of the thickness prescribed by the row of holes II are cast.

The particular means illustrated in the accompanying drawings as an embodiment of my invention will now be described.

Referring first to Fig. 2, it will be seen that the divisions 25 26 of the tripartite contact 23 are electrically connected, by means of conductors 25' 26', with the windings of a pair of electromagnets 25" 26". Said magnets are connected with a conductor 29 by wires 27 28, and said conductor 29 is connected with the return-wire 22 of the battery. Similarly the divisions 30 31 of the tripartite contact 24 are electrically connected by wires 30' 31' with the windings of a pair of electromagnets 30" 31", said windings being also connected to the return-wire 22 through wires 32 33 and the conductor 29. Above each of said magnets is arranged a contact-screw, it being carried by an angle-plate that is insulated from

the magnet. Between said contact-screws 1 vibrate armature-levers 34 35, which are insulated at their pivotal supports and are connected with spiral springs 36 37. On a conducting-pillar 38, arranged centrally between the pairs of electromagnets 25" 26" and 30" 31", is pivoted a connecting device having three arms 39 40 41. The arm 41 extends into the field of the electromagnets 25" 26" and is attracted by that one of the electromagnets of said pair which is energized, and thereby moves the arm 39 or 40 into contact with the upper angle-piece of the non-excited electromagnet. The said arm 41 has a spring-fork 47, with which the armature-lever 34 engages. The upper insulated angle-pieces of the electromagnets 25" 26" 30" 31" are electrically connected by wires 25^X 26^X 30^X 31^X with the windings of four electromagnets 25^{XX} 26^{XX} 30^{XX} 31^{XX}, which magnets are also connected by wires 42 43 44 45 to a bar 46, to which the return-wire 22 is attached. The operation of the electrical devices last described, which is controlled by the rows of holes I II of the perforated register, is as follows: If the row of holes I is in operative position under the points of the contact-springs 1' to 7' and the switch-lever 12 is moved to the tripartite contact 23, then as the sliding contacts 16 17 pass over the plates 6^X 6^{XX} a circuit is closed from the positive pole of the battery through the contact-spring 6', (which contacts with plate 8 through the hole in zone 6 of row I of the register,) the corresponding wire 9, the parts 6^X 17 15 16 6^{XX}, the corresponding wire 11, contact 6", contact 26, wire 26', electromagnet 26", and the wires 28, 29, and 22 to the negative pole of the battery. The electromagnet 26", which is energized by said current, attracts the armature-lever 34 and the arm 41, so that the lever comes into contact with the screw in the upper angle-piece of said electromagnet and the arm 39 contacts with the upper angle-piece of the electromagnet 25". The levers 34 and 39 are held in their adjusted positions by the spring 36 and by the engagement of the fork 47 of the arm 41 with the lever 34. Then during the same revolution of the shaft 13 as the sliding contacts 16 17 pass over the plates 3^X 3^{XX}, the row of perforations I of the register being still under the points of the contact-springs 1' to 7', and the switch-lever 12 over the tripartite contact 23, a circuit is closed from the positive pole of the battery to the plate 8, the contact-spring 3', (which rests against said plate through the perforation in zone 3 of row I,) the corresponding wire 9, the parts 3^X 17 15 16 3^{XX}, the corresponding wire 11, contact 3", the plate 48 of the tripartite contact 23, the wire 49, connected therewith, the armature-lever 34, the upper angle of the electromagnet 26", wire 26^X, the winding of the electromagnet 26^{XX}, and the conductors 43, 46, and 22 to the negative pole of the battery. The electromagnet 26^{XX} is consequently energized and its armature 50, Figs. 7 and 8,

attracted. By the movement of this armature a disk 51 (as explained later in the description of the mechanical part of the invention) is shifted the distance of three teeth, owing to the circumstance that the hole of row I now operative is in the zone 3 of the register. If instead of being in the register zone 3, the hole in row I, through which the second circuit is closed, were in the zone 1 2 4 5 the aforesaid disk instead of being moved a distance of three teeth would be moved one, two, four, or five steps, respectively. If the hole in row I through which the first of said circuits is closed was in the zone 7 of the register then, as is evident from Fig. 2, said first circuit would become closed as the sliding contacts 16 17 passed over the plates 7^X 7^{XX}, through the contacts 7" 25, wire 25', the electromagnet 25", and the conductors 27 29 22. The positions of lever 34 and arms 39 41 would thereby be the reverse of those previously described, and accordingly the second circuit would include the conductor 25^X 90 and the electromagnet 25^{XX}. The armature 52 of magnet 26^{XX} operates a disk 53, Figs. 7 and 8, and this disk would thus be moved a distance of three teeth, the operative perforation in row I being in zone 3 of the register 95 in the example selected. When the register-strip is advanced so that row II is brought into operative position under contact-springs 1 to 7', and the switch-lever 12 is adjusted over the tripartite contact 24, the first circuit closed during a revolution of the shaft 13 extends from the positive pole of the battery to the plates 7^X 7^{XX} (the row II in the example illustrated including a perforation in the zone 7 of the register) through a wire 105 11, the contacts 7" 30, the conductor 30', the electromagnet 30", and the conductors 32 29 22 to the negative pole of the battery. The energizing of the electromagnet 30" moves the armature-lever 35 into contact with the upper angle-piece of said magnet. During the remainder of the revolution of the shaft 13, while the row of holes II is still under the contact-springs 1' to 7' and the lever 12 is on the tripartite contact 24, the sliding contacts 110 16 17 pass over the contacts on the plate 10 and successively close (according to the hole combination illustrated in Fig. 1) three circuits, including the contacts 2^X 2^{XX} 3^X 3^{XX} 4^X 4^{XX}, the contacts 2" 3" 4", the part 54 of the 115 tripartite contact 24, the wire 55, the armature-lever 35, connected therewith, the upper angle of the electromagnet 30", wire 30^X, the electromagnet 30^{XX}, the conductor 44, bar 46, and wire 22 to the negative pole of the 120 battery. The electromagnet 30^{XX} will therefore be excited three times in succession, and thereby the armature 56 thereof will move a disk 58 three times in succession respectively two, three, and four teeth, making nine teeth 125 in all. With a different combination of holes in row II a corresponding different actuation of the disk 58 would be effected. If row II included a perforation in the zone 6 instead 130

of one in zone 7, as illustrated in Fig. 1 and assumed in the preceding description, the first circuit would include the parts 6", 31, 31', 31", 33, 29, and 22, and the armature 35 would be moved into contact with the upper angle-piece on magnet 31", and the three circuits last described would include electromagnet 31, wire 31^x, electromagnet 31^{xx}, and conductor 45, and the armature 57 of magnet 31^{xx} would actuate a disk 59.

From the explanation already given it is obvious that in cases where the entire spacing of a line permits of its being distributed equally to all the space-places without any remainder the register will not contain any row of holes like that designated I, and therefore when this unperforated section of the strip passes under the contact-springs 1' to 7' neither of the electromagnets 25^{xx} 26^{xx} will be energized. Similarly, in cases where the line can be spaced out exactly with spaces of medium normal thickness the register will not contain any row of holes corresponding to that marked II herein, and consequently when that section passes under the contact-springs 1' to 7' neither of the electromagnets 30^{xx} 31^{xx} will be excited. In these two cases the disks 53 51 or 58 59 will consequently not be moved out of their normal position. As previously stated, spaces (the thickness of which is determined previous to beginning to cast the type to form the line by the action of the rows I III) are cast as the rows III successively come into operative position.

As hereinbefore stated when explaining the principle of justifying according to which the present invention operates and as will be obvious, it is generally necessary to employ in a line two sizes of spaces, there being about one unit of difference in thickness between the two sizes. Means for insuring that when the desired number of spaces of one size has been cast the mold-core will be automatically adjusted so that thereafter spaces of a different size will be cast are also controlled by the rows of perforations III in the register. For this purpose when the hole in row III comes under the contact-spring 3', the circuit thereby closed, the switch-lever 12 being in the position illustrated in Fig. 2 causes an insulated contact-piece to pass between contact-springs 60 61, Fig. 2. The conductor 62, connected with contact 60, leads to the positive pole of the battery, while the other conductor 63, which is connected to contact 61, is in electrical connection with a contact-cylinder 64. A second contact-cylinder 65, operating alternately with 64 is connected by means of a wire 66 with the aforesaid pillar-conductor 38. This conductor 38 has an electrical connection with the arms 39 40 41, and therefore also, by means of the upper angle of that electromagnet 25" or 26", against which the lever-arm 39 or 40 rests, is electrically connected with the windings of the corresponding electromagnet 25^{xx} or 26^{xx} and through said magnet with the wire 22,

leading to the negative pole of the battery. It follows, therefore, that if the two contact-cylinders 64 65 come into electrical contact by means of the aforesaid contact-piece connecting the contact-springs 60 61 a circuit on the path given above is closed and, according to the position of the arms 39 40 41, the electromagnet 25^{xx} or 26^{xx} is energized, so that in one case the disk 53 and in the other case the disk 51 is advanced one tooth. In this respect it is to be stated as follows, having regard to the previous explanations: If at the beginning of the line the electromagnet 25^{xx} was excited by the row of holes I and the disk 53 consequently moved, then as the arm 40 comes in contact with the upper angle of the electromagnet 26" the electromagnet 26^{xx} would be excited by means of the row of holes III of the same line and the disk 51 advanced one tooth. On the other hand, if at the beginning of the line the electromagnet 26^{xx} was excited by means of the row of holes I and the disk 51 moved then, owing to the lever-arm 29 touching the upper angle of the electromagnet 25", the electromagnet 25^{xx} would be excited by means of the row of holes III of the same line and the disk 53 moved on one tooth. The contact-cylinders 64 65 are so arranged that, as shown in Fig. 5, when in their normal position they are not in electrical connection; but they come into electrical connection when the one is displaced with relation to the other. The two cylinders are mounted in a frame 67 and are adjustable longitudinally by pulling on arm 68, that project from rods connected to the cylinders. Cylinder 64 consists of two insulated metal casings 69 70, which are separated by a vulcanized-rubber ring 71 and electrically connected with each other by a metal spring 72. Cylinder 65 also consists of two insulated metal casings 73 74, with a metal ring 75 between them, which ring is capable of a slight movement laterally of the cylinder and is held against cylinder 64 by a spring 76, said spring forming at the same time a metallic connection between the casing 73 and the ring 75, while the electrical connection of the ring 75 with the casing 74 is insured by reason of the ring resting on the upper edge of this casing. In the normal position of the cylinders 64 65, as shown in the drawings, the metal ring 75 is in contact with the rubber ring 71, and the circuit through said cylinders and the conductors 63 66 is open. If, however, the cylinders are adjusted so that the ring 75 contacts with either casing 69 70, said conductors 63 66 are electrically connected, which connection lasts until by moving one of the cylinders the latter are brought into the relative position illustrated in Fig. 5, in which the rings 71 75 are in contact. The arm 68 of cylinder 65 is connected by a cord 77 with the periphery of disk 53, and the corresponding arm of cylinder 64 is connected by a cord with the periphery of disk 51, so that when these disks are moved the said cords are

wound thereon and the cylinders are raised correspondingly from their normal positions. By the action of the row of holes I one of the cylinders 64 65 is adjusted so that the cylinders come into electrical contact. Consequently each time a row of holes III comes into operative position the last-mentioned circuit over the electromagnets 25^{XXX} or 26^{XXX} will become closed by the contact-piece coming between the contact-springs 60 61, and this will be repeated until the other cylinder, which is thereby lifted step by step, is raised as high as the cylinder previously lifted by the action of the row of holes I. Having regard to the previous explanations and taking as a basis the row of holes I illustrated in Fig. 1, the whole operation will be as follows: By the action of the row of holes I the electromagnet 26^{XXX} is excited, the disk 51, attached thereto moved around three teeth, and its cylinder 64 raised a corresponding amount. The first row III of the perforated register following to the left then excites the electromagnet 25^{XXX} and moves its disk 53 around one tooth and raises the cylinder 65 one step, the said cylinder, however, not yet being as high as the cylinder 64, so that both are still in electrical contact and the next row of holes III can again excite the electromagnet 25^{XXX}. Consequently by means of the said row III disk 53 is again moved on one tooth and cylinder 65 raised a corresponding amount without yet rising to the same height as cylinder 64. The third row of holes III can therefore still excite the magnet 25^{XXX} and make the disk 53 advance a third tooth. By this movement the cylinder 65 is once more raised one step and now reaches the same height as the cylinder 64, (which was raised at one movement three teeth when row I was in operative position,) so that the rings 75 and 71 come into contact and the electrical connection between the two cylinders is broken. Consequently although each following row III of the line will adjust the contact-piece between the contact-springs 60 61 the circuit through the conductors 63 66 will not be closed and there will be no adjustment of cylinder 65. Finally when the hole IV comes into operative position both the cylinders 64 and 65 return to their original position, as shown in Fig. 5, and the disks 51 53 are returned into their first position by means of springs, so that at the beginning of a new line the cylinders and the disks are again in their normal position.

The mechanical part of the invention now about to be described is designed to transform the impulses of the electromagnets 25^{XXX} 26^{XXX} and 30^{XXX} 31^{XXX}, according to the signification of rows I, III, and II, into movement of the aforementioned disks and by means of these movements to adjust a piece 78, Figs. 7 and 8, which determines the thickness of the spaces to be cast and forms a stop for the core of the mold belonging thereto; also, to cause said stop to operate at the proper time, and, finally, at the end of a line to return the disks

53 51 58 59 and the cylinders 64 65 to their normal position.

The disks 51 53 (illustrated in section in Fig. 16) are provided on the edges of their adjacent faces with projections and recesses, as shown more particularly in Fig. 17. The projections of the disk 51 are double-stepped, and the lower steps 79 only extend sufficiently far so that when the disk 51 (see inner view, Fig. 15) is moved in the direction of the arrow a distance controlled by a single tooth 80 the steps 79 release the teeth 81 of the disk 53, so that the two disks can then be moved closer to each other a distance equal to the width of spaces 82 83, which corresponds to a decrease of one unit in relation to the spaces in the common thickness of the two disks. The distance between the edges 85 84 is calculated so that disk 51 can be moved around five teeth without its steps 86 coming in contact with the steps 81 of the disk 53, while, as before explained, disk 51 (and disk 53) is at most moved around five teeth. If, on the other hand, disk 53, which, like disk 51, is provided on the edge with teeth, is moved in the direction of the arrow—that is, in the same direction as disk 51—its steps 81 will come in front of the steps 86 of the disk 51, so that both disks are moved apart out of the position illustrated in Fig. 17 the amount of the double gap 82 or 83, which is equal to an increase of one unit in relation to the spaces in the common thickness of the two disks. At the same time it will be seen from the above, with reference to Fig. 17, that if one of the disks is moved a certain number of teeth (one to five) and the other disk afterward moved the same number of teeth both disks will thereupon assume the position with regard to each other illustrated in Fig. 17. The disks 58 59 have at the edges of their adjacent faces two cam-surfaces 87 88 and 89 90 or 87' 88' and 89' 90', respectively, which ascend from 87 to 88 and from 89 to 90 and from 88' to 87' and from 90' to 89', respectively. The disks 58 59, which in Figs. 19 and 21 are represented as separated to a considerable extent for the sake of clear illustration, in reality touch each other with their cam-surfaces, and their normal position with regard to each other is that shown in Figs. 18 and 20, in which the central line x y is covered by the line x' y'. If the disk 58 is moved in the direction of the arrow, Fig. 18, from this normal position, the cam-surfaces of both disks move apart, which results in an increase in the common thickness of the two disks by as many units as the number of teeth 91 which the disk 58 is advanced. If, on the other hand, disk 59 is moved from its normal position in the direction of the arrow, Fig. 20—i. e., in the same direction as disk 58—around a given number of its teeth 91', a corresponding gap will arise between the cam-surfaces of the two disks, so that they can be adjusted close to each other, which is equal to decreasing the common thickness of the

two disks by as many units as the number of teeth 91 moved. The disks 51 53 58 59 revolve on a pivot 92, which is located in the frame 93 of the machine and has one flattened end 94, securely fixed in a block 95 to prevent its turning. The pivot 92 extends through a sleeve 96, revolubly mounted in the frame 93, which sleeve carries a fixed disk 97. This latter bears, Fig. 8, on the left side against the frame of the machine and serves as a support at the left side for all of the disks when the outer disk 59 is pressed to the left. The pivot 92 bears a fixed tie-disk 98, and between this and a second disk 99, fixed on said pivot, is revolubly mounted a disk 78, Figs. 7 and 8. With this latter disk engages a double lever 101 102, which is pivoted at 100, Fig. 7, so that when this lever is rocked by a pin 103 the disk 78 is adjusted into the position illustrated in Fig. 12 and its projecting piece 104 comes into the path of an adjustable stop-screw 106, which is fixed on the core-carrier 105 of the mold, Fig. 8. In this manner the core-carrier, advancing under spring-pressure toward the disk 78 receives a variable stop, the adjustment of which varies according to the extent of displacement of the disks 51 53 and 58 59 from their normal positions. The pressure of the screw 106 is transmitted by means of the tie-disk 98 to the disks 59 58 53 51 97 and finally absorbed by the frame of the machine. As the pivot 92 is adjustable longitudinally, if the united thickness of the disks 51 53 58 59 is decreased it will move to the left under pressure of the core-carrier against the disk 78 until these disks are closed against each other, while when the united thickness of the disk is increased the disk 78, with the pin 92, moves to the right. The adjustment of the core-carrier and the core 107 corresponds to the width of the casting-slot 108, Fig. 9, and the thickness of the spaces to be cast. If the disks 51 53 58 59 are in their normal position, Figs 17, 18, 20, the core is adjusted for casting spaces of medium normal thickness. If, on the other hand, the disks have been moved out of their normal position, the core-carrier 105 is correspondingly adjusted and thicker or thinner spaces are cast, varying from the normal space by a number of units corresponding to the adjustment. The pin 103 is only actuated for rocking the lever 101 102 and the disk 78 when a spacing-hole III comes under the contact-spring 1' to 7', so that although an adjustment of the disk 78 in the direction of the length of pivot 92 is effected as the rows of holes I II become operative through movement of the disks 51 53 58 59, said disk 78 only comes into operation when the spaces are cast. In casting type (between the spaces) lever 101 102 occupies the position indicated in Fig. 7, the disk 78 being out of the path of the striking-screw 106 of the core-carrier, which is capable of being adjusted by other means, not forming part of the present invention, to the thick-

ness of the type to be cast. (See United States Letters Patent No. 628,631.)

The rotation of the disks 51 53 58 59 to an extent equal to the number of teeth corresponding to the hole combinations I II is effected by the following means, (see Figs. 7, 8, 10:) On a continuously-revolving shaft 109, which is synchronized with the shaft 13, Fig. 2, is secured a cam 110, having six peripheral steps 111 112 113 114 115 116. The steps 111 and 116 project an equal distance beyond the periphery 117 of the disk, while the steps 112, 113, 114, and 115 project two, three, four, and five times as far beyond said periphery. A roller 121, carried by a double-lever 119 120, fulerumed on a pivot 118, is kept constantly against the edge of the cam 110 by means of a spring 122, so that said lever is continuously rocked as the steps 111 to 116 pass said roller. The forked free end of lever-arm 120 engages a pin 123 on disk 97, which disk has a projecting edge 124, that is connected with a segment 126, Figs. 7 and 10, by means of an arm 125, Figs. 10 and 11, said arm extending past the disks 51 53 58 59. A spindle 127 has its ends journaled in the segment 126 and the edge 124 of the disk 97, and on said spindle are fixed a series of projections 128 129 130 131 132. The projection 128 is arranged close to the segment 126, while the other projections are adapted to engage pins 133 on pawls 134 135 136 137, loosely mounted on the spindle 127. The projections 129 to 132 and pawls 134 to 137 are so distributed on the spindle that the pawls lie in the planes of the toothed rims of the disks 51 53 58 59, so as to be able to engage with the teeth of said toothed rims. The teeth of the pawls are so wide that even if the disks 53 58 59 are moved laterally the toothed rim thereof will remain in engagement with the pawls. The pawls 134 to 137 are caused to engage with said toothed rims by means of leaf-springs, arranged between said pawls, and a pin or rod 138, extending between segment 126 and the disk edge 124, but are normally held out of engagement by means of catches 139 140 141 142. These catches are pivoted on a pin or rod 143 and by means of springs arranged between their lower arms and the rod 138 are pressed toward the pawls, the free upper ends of the catches engaging over the knife-edged ends of the pawls. In the normal position of the lever 119 120, which controls the movement of this system of pawls, (illustrated in Fig. 7,) the projection 128 is, by the pressure of spring 122, pressed against a stop 148 on the machine-frame, and the pawls 134 to 137 are prevented by the projections 129 132 from engaging with the toothed rim, even if the catches 139 to 142 are inoperative. When, however, lever 119 120 is actuated against the pressure of the spring 122 by means of the cam-steps 111 to 116, the projection 128 is immediately released by the movement of segment 126, so that the projections 129 to 132 offer no ob-

struction to movement of the pawls 134 to 137 toward the justifying-disks, and therefore those pawls which are released by their catches 139 to 142 engage with their respective toothed rims and move the disks engaged according to the stroke given by the lever 119 120. The several parts are of such size and so related that by accurately regulating an adjustable stop 148 the disks 51 to 53 58 59 will be shifted two, three, four, or five teeth, respectively, by means of the steps 111, 112, 113, 114, or 115. The step 116, which corresponds with 111, likewise effects a movement of one tooth. The catches 139 to 142 are released by energizing the electromagnets 26^{xx} 25^{xx} 30^{xx} 31^{xx}. The armatures 50 52 56 57 of these magnets are each connected to one arm of a two-armed lever 149, which lever is pivoted on the frame of the machine and connected with said armatures by rods 150. The other arms of said levers act on the lower arms of the catches and are adapted to adjust them into the position illustrated in Fig. 11. The notches 151 in the lower arms of the catches serve to prevent the levers 149 from being thrown back prematurely under the influence of the armature-springs 152, so that the levers can only slip back into the normal position, Fig. 7, when the lever 119 120 begins its stroke. As previously stated, the shafts 13 and 109 rotate with regular and synchronized motion. The steps 111 105 115 of the cam 110 are arranged so that the roller 121 passes over the steps 111 112 113 114 115 synchronously with the passing of the sliding contacts 16 17 over the separate pairs of plates 1^x 1^x 2^x 2^x 3^x 3^x 4^x 4^x 5^x 5^x and preferably in such a manner that at the moment when the contacts leave a pair of plates o the corresponding step of the cam 110 begins to act on the roller 121. The consequence of this synchronizing of the parts is (reference being had to the previous explanation) that when the rows of holes I or II come into operative position the disks 51 or 53, or 58 or 59 are moved around as many teeth as is indicated in units in the zones 1 to 5 of these rows, the disks 53 and 58 being moved if those rows contain a hole in the zone 7, and the disks 51 and 59 if the rows contain a hole in the zone 6. In accordance therewith the disk 78 is so adjusted that spaces are cast which are thicker or thinner than the normal medium-sized space by the necessary number of units. It is evident that the steps of the continuously-revolving (even when the machine is casting letter-types) cam 110 effect the rocking of the lever 119 120 and the system of pawls, but do not move the disks 51 53 58 59 unless the electromagnets 25^{xx} 26^{xx} 30^{xx} 31^{xx} are energized at the same time. Likewise, also, the step 116 does not effect any movement unless one of the electromagnets 25^{xx} 26^{xx} 30^{xx} 31^{xx} is energized at the time step 116 passes roller 121. This happens as regards the electromagnets 25^{xx} or 26^{xx} when, as previously explained, a contact-piece comes

between the contact-springs 60 61, Fig. 2, when row III of the register-strip is in operative position and a circuit over one or other of the said electromagnets is closed, provided that (as will be recollected) the contact-cylinders 64 65, Figs. 5, 6, are in electrical contact with each other. Then when the step 116 passes on disk 51 or 53 is moved a distance of one tooth, according as the circuit is closed over the electromagnet 25^{xx} or 26^{xx}.

The disks 51 53 58 59 are fastened to spiral springs 155 by means of cords 153, Fig. 7 which are secured in peripheral grooves in the disks, Figs. 16, 21, said springs being fixed at one end to the frame of the machine. The disks are kept in their normal position by means of these springs and after the movement taking place at the end of the line 85 are returned thereby to such normal position, in which they are supported by means of a step 156, contacting with a lug 157 on the machine-frame. The cords of disks 51 53 are also connected with the arms 68 of the contact-cylinders 64 65, as shown by the line 77. In the normal position of the disks 51 53 the cylinders 64 65 are also in their normal position, (see Fig. 5,) in which they are not in electrical contact. As previously explained, 95 when a row I comes into operative position one of the disks 51 53 is moved a certain number of teeth and its respective cylinder is correspondingly raised. Then as the several rows III come into operative position the other of said disks is successively moved on one tooth and the other contact-cylinder is correspondingly raised until both disks and cylinders resume their normal positions with regard to each other, Figs. 17 and 5. This latter movement of one tooth at a time is effected by means of the step 116 of the cam 110. As the disks 51 53, (see the previous explanations with reference to Figs. 15, 16, and 17,) now in their normal position with regard to each other, represent an intermediate piece which is thicker or thinner by a given amount than their common thickness after they have each been displaced from their normal position, it follows that as soon as they have returned to their normal position the disk 78 will be displaced before the casting of the next space. The steps of the disks are arranged so that this displacement amounts to one units-space. Therefore after 120 the disks 51 53 have assumed their mutual normal position the casting of the spaces of one "sort" ceases and the casting of the second "sort" of spaces differing by the thickness of one unit from the first sort begins, as has 125 been previously explained. In order to secure the disks 51 53 58 59 in their position after each movement against the pull of the spring 155, a lever 158 is pivoted to the frame at 100, Fig. 7. A spring 159 acts against a horizontal arm 160, provided with a series of spring-catches 161, in such a manner as to cause said catches to engage the toothed rims of the disks. When the hole IV of a line

comes into operative position, a pin 162 is actuated, which pin presses against the lower arm of the lever 158, thereby turning the lever into the position shown in Fig. 13, and thus raising the catches 161 out of the toothed rims of the disks, which latter are then, by means of the springs 155 and cords 153, returned to their normal position in order to be actuated again for the spacing of the next line.

As the spacing is distributed over not more than ten space-places and the other places are to receive spaces of normal thickness, while for the correct adjustment of the disk 78 for casting these normal spaces the disks 51 53 58 59 must resume their normal position, it therefore results that in lines with more than ten space-places the disks 51 53 58 59 must be restored to their normal position before the eleventh space has been cast, so that the eleventh and following spaces are cast in the normal position of these disks. For this purpose lever 101 102, Figs. 7, 12, 13, 14, carries on its axle 100, which is journaled in the piece 163 of the machine-frame, a lever 164, having a spring-actuated pawl 165, which engages a ratchet-disk 166, loosely mounted on the axle 100, and moves the said disk around one tooth every time the lever 101 102 performs a stroke every time a space is cast. The disk 166 has a projection 167, which is connected with a spring 168 and is arrested after each movement by means of a spring-actuated catch 169 on the lever 158. After ten movements the disk 166 with its projection touches the catch 169, as shown in Fig. 12. At the eleventh movement of the disk 166 the projection 167 moves the lever 158 by means of the catch 169, and thus lifts the catches 161 out of the toothed rims of the disks 51 53 58 59. These disks thereupon spring back into their original positions before the eleventh space is cast, so that the eleventh and following spaces are made of normal thickness. If at the end of the line the pin 162 is actuated by the operation of hole IV, Fig. 13, while lever 101 102 assumes its normal position (illustrated in Fig. 13) and lever 158 is displaced, then a pin 170 on lever 158 raises the catch 165 and a stoppin 171 withdraws catch 169 from the ratchet-disk 166, so that the latter also can return to its normal position under the influence of the spring 168 in order to resume its function at the beginning of the next line. If the line has only ten or less than ten space-places, the parts come into the position illustrated in Fig. 13 before the projection 167 of the disk 166 becomes operative—*i. e.*, before it reaches the catch 169—so that in this case also the disk 166 is returned to its normal position at the end of the line.

In concluding there may be referred to a modification of the disk 110, Fig. 7. The present invention in its principle of the spacing in general limits the combinations of the

holes of rows I and II to the zone-lines 1 to 4. The hole in the zone-line 5 can be preferably reserved for special cases—namely, for exceptional cases where the lines have few space-places in proportion to their length, and therefore require spaces differing in thickness very much from the normal spaces. For this purpose the zone-line 5 signifies ten units, and the step 115 of the disk 110 projects twice as far from the periphery of said disk, as shown in dotted lines by 115'. Therefore when this step passes the roller 121 the operating disk is moved around ten teeth and the spacing altered by ten units.

Having now particularly described and ascertained the nature of my said invention and in what manner the same is to be performed, I declare that what I claim is—

1. A device for casting justifying-spaces in combined type casting and setting machines operated by means of a perforated register-strip, consisting in the combination of a combined stop for the core of the mold, the said stop being composed of adjacent pairs of 90 wedges and counter-wedges and steps and counter-steps, means for relatively shifting to each other the said wedged and stepped pairs and thereby adjusting the stop for casting spaces of different thickness, and means for 95 restoring the said pairs to their initial position after the spaces of one line have been cast, substantially as and for the purposes described.

2. A device for casting justifying-spaces in combined type casting and setting machines operated by means of a perforated register-strip, consisting in the combination of four ratchet-disks adjacent to each other and movably mounted on a common axis, one pair of 100 the same being provided at their opposed sides with wedge-shaped surfaces, and the other pair of disks being provided at their opposed sides with steps, means for shifting relatively to each other the disks of each pair, means for restoring the stepped disks to their initial position after a predetermined 105 number of spaces of one kind has been cast in order to adjust the stop for the casting of a second kind of spaces, and means for restoring the wedged disks to their initial position after the spaces for one line have been cast, substantially as and for the purposes 110 described.

3. A device for casting justifying-spaces in combined type casting and setting machines operated by means of a perforated register-strip, consisting in the combination of a combined stop composed of a system of spring-actuated adjacent wedge-shaped and stepped 120 ratchet-disks movably mounted on a common axis, an oscillating frame provided with pawls to engage with the said ratchet-disks, a system of catches to keep the several pawls inoperative, means for releasing the pawls from the catches in accordance with the justifying-holes of the register, and arresting-pawls for 125 130

keeping the disks against the pull of their springs after each shifting movement, substantially as and for the purposes described.

4. A device for casting justifying-spaces in combined type casting and setting machines operated by means of a perforated register-strip, consisting in the combination of a system of adjacent wedge-shaped and stepped disks movably mounted on a common axis, a movable abutment mounted on the same axis and bearing against the said combined stop, means for removing the said abutment out of the path of the mold-core, when casting letter-types, and means for swinging the abutment into the path of the mold-core before the casting of each justifying-space, substantially as and for the purposes described.

5. A device for casting justifying-spaces in combined type casting and setting machines operated by means of a perforated register-strip, consisting in the combination of a system of spring-actuated ratchet-disks, a system of arresting-pawls to keep the disks against the pull of their springs, and means for disengaging the said arresting-pawls from the ratchet-disks at the end of a line in order to allow the said disks of being restored by their springs to their normal position, substantially as and for the purposes described.

6. A device for casting justifying-spaces in combined type casting and setting machines operated by means of a perforated register-strip, consisting in the combination of a combined stop composed of a system of spring-actuated adjacent wedge-shaped and stepped ratchet-disks movably mounted on a common axis, an oscillating frame provided with pawls to engage with the said ratchet-disks, a system of catches to keep the several pawls inoperative, a cam-disk provided with stepped projections to actuate the said oscillating frame, a revolving shaft carrying a pair of sliding contacts to pass on a system of pairs of contact-plates, the said contact-plates being passed by the sliding contacts in synchron-

nism with the several oscillations of the oscillating frame in order to open several electric circuits and thereby exciting corresponding electromagnets in accordance with the hole 50 combinations of the perforated register, and means actuated by the electromagnets to release the corresponding pawls from their catches so as to engage with the corresponding disks and shift the same in accordance 55 with the stroke of the oscillating frame, substantially as and for the purposes described.

7. A device for casting justifying-spaces in combined type casting and setting machines operated by means of a perforated register-strip, consisting in combination of a system of adjacent wedge-shaped and stepped disks movably mounted on a common axis, means for shifting relatively to each other the wedge-shaped disks and the stepped disks at 65 the beginning of the line by means of two hole combinations of the register respectively, becoming operative after each other, and means for step by step restoring the stepped disks to their normal position by means of 70 hole combinations of the register provided between each two words, substantially as and for the purposes described.

8. A device for casting justifying-spaces in combined type casting and setting machines 75 operated by means of a perforated register-strip, consisting in the combination of a system of spring-actuated ratchet-disks, a system of arresting-pawls to keep the disks against the pull of the springs, and means 80 for disengaging the said arresting-pawls from their corresponding disks after a predetermined number of justifying-spaces have been cast, in order to distribute the justifying over a limited number of spaces, substantially as 85 and for the purposes described.

In witness whereof I have hereunto set my hand in presence of two witnesses.

COLOMAN ROZÁR.
